UNITED STATES PATENT OFFICE.

JULIUS H. SCHLAFLY, OF CANTON, OHIO.

METALLIC FLUME.

1,113,251.

Specification of Letters Patent.

Patented Oct. 13, 1914.

Application filed November 23, 1911. Serial No. 661,985.

To all whom it may concern:

Be it known that I, JULIUS H. SCHLAFLY, a citizen of the United States, residing at Canton, in the county of Stark and State 5 of Ohio, have invented certain new and useful Improvements in Metallic Flumes; and I do hereby declare that the following is a full, clear, and exact description of the invention, such as will enable others skilled 10 in the art to which it belongs to make and use the same.

The present invention relates to flumes, especially designed for water troughs used for irrigating and analogous purposes.

15 The objects of the present invention are, first, to provide a flume made up of sections of such a length or lengths that can be conveniently shipped and placed in position. Second, to provide means for so connecting the sections together that the entire 20 length of the trough or flume will present an even and smooth surface. Third, to provide means for securely clamping the joined ends of the sections together and in such a 25 manner that they will not be liable to become detached from any ordinary cause. Fourth, to provide means for adjusting the trough with reference to its supports or hangers, and at the same time adjust the 30 trough from time to time at such places as may be necessary by reason of any sagging or movement of the supporting frame.

With these objects together with others the invention consists in the construction 35 and arrangement of the parts as will be hereinafter more fully described and illustrated in the drawings.

In the accompanying drawings, Figure 1 is a perspective view showing portions of 40 two sections and one full section, one completed joint and hanger, also one joint and its different parts disconnected. Fig. 2 is a longitudinal section on line 2—2, of Fig. 3. Fig. 3 is a transverse section on line 45 3—3, of Fig. 2. Fig. 4 is an enlarged fragmentary sectional view on line 4—4, Fig. 3. Fig. 5 is a longitudinal section showing one 50 modification of joint. Fig. 6 is a longitudinal section showing still another or second modification of joint. Fig. 7 is a longitudinal section showing a third modification of the joint. Fig. 8 is a transverse section on line 8—8, Fig. 7.

Similar numerals of reference indicate 55 corresponding parts in all the figures of the drawings.

In the accompanying drawing, 1 represents the sections which are preferably formed of sheet metal and are semi-cylindrical in cross section. The sections may be 60 formed of any desired length, reference being had to convenience in manufacture, shipping and assembling. The sections may be formed of various sizes, reference being had to the capacity of the finished trough. 65

In use, especially for irrigating it frequently is necessary to construct a trough of considerable length and to support the various sections going to make up the completed structure above the ground, as for instance it is desired to conduct water across a valley or depression and at the same time maintain the proper grade or inclination so that water may be if necessary carried over elevations. In order to accomplish this result it is frequently necessary to construct trestle work or other frame work of considerable height and at other points such trestle or frame work may be comparatively low, but as a rule the trough is to be supported throughout its entire length by suitable cross bars or hangers 2 which cross bars or hangers are supported by suitable frame work or walls as the case may be. As shown the sections which are non-corrugated are preferably formed without corrugations so that the bottom of the trough or the surface upon which the water flows is smooth, thereby offering the least resistance to the flow of water. 90

For the purpose of joining the sections together the ends of the sections are provided with the semi-circular channels 3 and the channel portions lapped one upon the other, the extended or outer portion 4 fitting into the channel portion of an adjacent section. The inner clamping bar 5 is located in the channel of the end of the section seated in or lapped in the adjacent section as illustrated in Fig. 2. The outer 95 clamping bar or yoke 6 is located upon the bottom or underside of the underlapped section. This outer clamping bar or yoke is screw threaded at its ends, which screw threaded portions are passed through suitable apertures formed in the hangers 2. Upon the screw threaded portions of the yoke 6 are located the tie-blocks 7, the nuts 8, 9 and 10. The tie blocks 7 are provided with the grooves 11, which grooves receive 100 the top or upper ends of the inner clamping bar 5, and the screw threaded ends of the 105

yoke 6 pass through the apertures 12 formed in said tie-blocks. The nuts 8 are located upon the tie-blocks and are for the purpose of securely holding said tie-blocks in proper relative position. The nuts 9 are for the purpose of forming rests or seats for the hanger bars 2, directly above the connected ends of the yoke 6. The nuts 10 which are located above the hanger bars 2 are for the purpose of holding the flume or trough sections in proper relative position with reference to the hanger bars 2. If desired metal washers 13 may be placed upon the tops of the hanger bars 2 and the nuts 10 placed on the top faces of said washers, but this construction is mechanical and may be dispensed with if desired.

For the purpose of assisting in holding the yoke, or more specifically from preventing the same from slipping laterally upon the bottom or underside of the trough section, parallel ribs 14 are provided, which ribs are pressed or stamped from the channel portions of the sections. In Fig. 1 these parallel ribs are located in pairs and the pairs are spaced from each other leaving plain portions intermediate the parallel ribs.

In Fig. 5, a slight modification is illustrated, which slight modification consists in forming the ribs 15 continuous instead of forming the ribs in pairs and spacing the same and in Fig. 6 the yoke 16 is shown angular in cross section instead of round and by so forming the yoke a sufficient surface is provided to frictionally hold the yoke in proper relationship with reference to the section it comes in contact with without the aid of parallel flanges. In Figs. 7 and 8 spaced nibs 17 are punched from the channel portions of the sections and the yoke 6 located between pairs of nibs 17. The modifications shown in Figs. 5, 6 and 7 are simply mechanical in their nature as it is well understood that the only purpose is to provide some mechanical means for properly holding the yoke in position. The clamping devices and the suspending devices being practically the same, regardless of the modifications shown in Figs. 5, 6 and 7.

In the maintenance of flumes it is of importance that the proper inclination be maintained throughout the entire length of the flumes, but the frame work supporting the flume is liable to sag more in some places than others by reason of variations of the ground upon which the frame-work is supported, or by reason of freezing which has a tendency to disrupt the true alinement of the frame-work; and in order to provide for this variation it is of importance to provide some means by which the flume can be maintained in true alinement or in other words to provide means for adjusting the flume up or down independent of the frame-work or

more specifically without disturbing the positions of the cross bars or hangers 2. In order to provide for this adjustment it is only necessary to change the positions of the nuts 9 and 10 adjusting said nuts upon the screw threaded portions upon the yoke 6, so as to permit said yoke to be lowered or elevated with reference to the cross bars 2. This adjustment either up or down can be made without disturbing in any manner the clamping bars 5.

Flumes designed and calculated for irrigating purposes are frequently formed of considerable size for the purpose of conducting a sufficient amount of water for the purpose designed.

It is well understood that there is more or less friction as between the running water and the trough or channel through which the water flows and consequently there is considerable force brought upon the suspending trough or flume and consequently it is of importance to provide a flume having as little resistance to the flow of water as possible throughout its entire length. By forming the flume sections with smooth surfaces and seating the clamping bars 5 in the channels formed at the ends of the sections very little resistance to the flow of water is offered, thereby reducing to a great extent the strain upon the flume, owing to the fact that there is nothing in the bottom of the flume to resist or impede the flow of water save and except the continuous smooth bottom of the flume. It is well understood that in flumes where slight ridges are located at the joints there is more or less banking of the water which greatly increases the tendency to cause the trough or flume to move with the flow of water and hence the tendency to disrupt the true alinement of the flume.

Having thus described my invention, what I claim as new and desire to secure by Letters Patent, is—

1. A metal flume consisting of a series of sections, the ends of the sections provided with channels and the channels of adjacent sections adapted to be seated one within the other, a clamping bar adapted to be seated in the channel of one of the sections, a yoke provided with screw threaded portions, tie blocks mounted upon the yoke, said tie blocks provided with grooves and the ends of the clamping bar adapted to be seated in the grooves, nuts mounted upon the yoke and in contact with the tie blocks, a hanger bar and means for adjusting the yoke with reference to the hanger, substantially as and for the purpose specified.

2. A flume consisting of a series of sections joined together at their ends, suspending hangers, and means for adjusting the flume sections to or from the suspending hangers.

3. In a flume of the class described, a series of sections joined together, means for clamping the joined ends of the sections, suspending hangers, and means for adjusting the flume sections to or from the suspending hangers.

5 In testimony that I claim the above, I

have hereunto subscribed my name in the presence of two witnesses.

JULIUS H. SCHLAFLY.
